UNITED STATES PATENT OFFICE

2,524,005

SPRING POWERED ELECTRIC GENERATOR

Gottfred Boe, Englewood, N. J., assignor to
Specialties, Inc.

Application May 27, 1948, Serial No. 29,549

4 Claims. (Cl. 290—1)

1

The present invention relates to spring powered electric generator units of the type producing for a fraction of a second a current of predetermined amperage and voltage.

The invention has been developed more particularly in the production of a generator unit designed for emergency use of airplane pilots to ignite a number of explosive squibs which initiate the operation of means permitting escape of the pilot from a pressurized cockpit. Such an embodiment of the invention will be more particularly described for the purposes of disclosure of the principles of the invention but it will be understood that the description is illustrative and is not intended as restrictive.

The principal object of the invention is to provide a spring powered generator unit which is reliable and as nearly accident proof as possible in use.

The invention aims to provide a unit, the operation of which can be initiated by the pilot by a simple movement requiring little effort.

The invention aims further to provide an indicator by which the pilot can readily know whether the spring motor is suitably wound and ready for operation.

Another object is to include provision for automatic operation of a switch to connect the generator to the work circuit for operation and to restore the circuit to normal condition after such operation.

Other objects, and the nature of the invention, will more fully appear from a description of an illustrative apparatus embodying the principles of the invention for the purposes of which description reference should be had to the accompanying drawings forming a part hereof and in which:

Figure 1 is a central sectional view of the complete mechanism.

Fig. 2 is a detail sectional view of the ratchet taken on the line 2—2 of Fig. 1.

Fig. 3 is a detail sectional view of the stop mechanism taken on the line 3—3 of Fig. 1.

Fig. 4 is a sectional view taken on the line 4—4 of Fig. 1, but showing the cam and switch in squib firing position.

Fig. 5 is a sectional view showing the spring motor taken on the line 5—5 of Fig. 1.

Fig. 6 is a central sectional view of the protective cover.

Fig. 7 is a view of the indicator disk taken on the line 7—7 of Fig. 1.

A spring motor 5 drives a generator 6 through suitable gearing to provide a current for igniting

2

a set of squibs. The spring motor comprises two similar spiral springs 7 and 8, the outer ends of which are anchored on a transverse pin 9, Fig. 5, fixed in the casing and the inner ends of which 5 are anchored in a slot 10 in a driven shaft 11 rotatable in ball bearings 12 and 13. As a safety provision, each spring is strong enough to provide the necessary power for operation whereby any 10 accidental failure of one spring will not make the device inoperative. A washer 14 separates the two springs. When the spring motor drives shaft 11, gear 15 keyed thereon drives pinion 16 secured to or formed on generator drive shaft 17 rotatably supported in a ball bearing 18 in the 15 casing and on the ball bearing 19 on the end of the generator shaft 20. The generator shaft, with the generator rotor 6 rigidly secured thereto, is carried in ball bearings 21, 22 and driven through an overrunning clutch 23. The overrunning clutch permits winding of the spring motor without turning the generator rotor and permits free overrunning of the generator rotor after operation of the device. By this arrangement, no great strain is applied to the 20 spring motor or other parts of the mechanism when after operation certain parts are stopped at the point of complete unwinding of the spring motor.

To wind the spring motor, shaft 17 is turned by hand wheel 25 on shaft 26 while in its outermost position as pressed outward by a spring 27 compressed between the hand wheel and the casing at 28 where the shaft 26 extends through the casing.

Shaft 26 is formed to provide a ratchet wheel 29 and a clutch member 30. The ratchet teeth are engaged by pawl 31 to prevent reverse rotation of the shaft and are long enough to be engaged thereby in all positions of the longitudinal movement of the shaft. The clutch element 30 35 engages the clutch element 32 formed on the outer end of the drive shaft 17 when, but only when, the hand wheel is in its outer-most position. The clutch elements as shown are hexagonal. When engaged, the clutch connects the shafts for winding of the spring motor and also provides a lock to prevent rotation of the shaft 17 as actuated by the spring motor. To release the lock for starting of the motor and for operation of the generator, the pilot simply pushes the hand wheel 25 against the relatively small pressure of the spring 27. As the clutch member 30 moves inward the spring pressed ball detent 34 will ride over the shoulder 35 and resist 40 return movement of the hand wheel and asso-

ciated parts. The spring motor then drives the generator to cause ignition of the squibs.

Preferably the hand wheel is protected by cover 36, hinged at 37 to prevent operation of the device by accidental pressure on the hand wheel.

A signal device is provided to indicate the fully wound condition of the spring motor and to provide a warning signal if the spring motor is not fully wound and ready for operation. As shown, a disc 40 secured on the end of the shaft 11, is visible through a window 41 in the casing. When the spring motor is fully wound a green or white portion 42, Fig. 7, of the disc registers with the window, thus indicating that the device is in condition for operation. In any other position a red portion of the disc is visible. The collar 43 securing the disc on the shaft also reinforces the slotted shaft 11 at its outer end.

A limiting device is provided to prevent overwinding of the spring motor while permitting more than one complete rotation of the shaft 11 and gear 15. As shown, a pin 45 projecting from the side of the gear 15 will engage, during the first part of the winding operation, an arm 46 rotatable upon the shaft 11 and turn it until it comes against a stop 47, Fig. 3, fixed in the casing. The spring motor is then fully wound. When the device is operated, pin 45 moves away from the arm 46 and after nearly a complete rotation of shaft 11 engages the other side of the arm and can still rotate a considerable part of a second turn.

Switch mechanism is provided automatically to connect the generator to the work circuit for emergency operation and after operation to again disconnect the generator from the work circuit. Actually in the apparatus for which the invention was more particularly developed the switch 50, Fig. 4, in normal position connects a battery to the work circuit but in its emergency position as activated by the cam 51 it disconnects the battery and connects the generator to the same work circuit for the emergency operation. After the operation is complete the cam causes the switch again to connect the battery to the work circuit. The switch 50 and the cam 51 are best shown in Fig. 4. When the spring motor is fully wound and the device is ready for action, the follower 52 of the switch is on the low part of the cam and the work circuit is connected to the battery and not to the generator. As the spring motor is released and starts to rotate the cam, the high portion of the cam engages the follower causing the switch to disconnect the battery from the work circuit and to connect the generator thereto for a sufficient period of time for operation. Further rotation of the cam disconnects the generator and restores the connection between the work circuit and the battery. It is to be noted that during the start, and the operation of the spring motor through a predetermined angle, the generator circuit is open and therefore there is no load on the generator to resist a quick pick-up.

The design of the springs 7, 8 is such that failure of either spring is extremely unlikely, however, if failure occurs it will probably occur near the inner end and the broken spring will expand within the drum and assume a position such that the rotation of the shaft 11 will not be obstructed thereby.

Each spring is of sufficient strength to alone drive the generator and produce the necessary voltage. This provides a safety feature for effec-

tive operation even in the event of failure of one spring.

The description of a particular embodiment of the invention is for the purposes of illustration and is not intended as defining the limits of the invention.

I claim:

1. A spring powered electric impulse generator of the character described comprising in combination a spring motor having dual springs jointly independently capable of operation; a shaft driven by said spring motor; an electric generator having a shaft to be driven; gearing connecting said shafts for operating said generator from said spring motor; an overrunning clutch between said generator and its shaft to permit of winding said spring motor without turning said generator; a clutch associated with said gearing to permit winding of said spring motor in one position and rotation of said generator by said spring motor in another position; an operating shaft for said clutch; a spring loaded winding knob on said operating shaft adapted in one position when pressed against its spring loading to establish rotation of said generator from said spring motor, and in another position when spring loaded to its fullest extent to permit winding of said spring motor; a switch normally disconnecting said generator from a work circuit; and a cam mounted to be operated by release of said spring motor to connect said generator in said work circuit, whereby said generator can apply an impulse thereto.

2. A spring powered electric impulse generator of the character described comprising in combination a spring motor; a shaft driven by said spring motor; an electric generator having a shaft to be driven; gearing connecting said shafts for operating said generator from said spring motor; an overrunning clutch between said generator and its shaft to permit of winding said spring motor without turning said generator; a clutch associated with said gearing to permit winding of said spring motor in one position and rotation of said generator by said spring motor in another position; an operating shaft for said clutch; a winding knob on said operating shaft adapted in one position to establish rotation of said generator from said spring motor, and in another position to permit winding of said spring motor; a switch normally disconnecting said generator from a work circuit; and a cam mounted to be operated by release of said spring motor to connect said generator in said work circuit, whereby said generator can apply an impulse thereto.

3. As an emergency unit for the purposes described, a spring powered electric impulse generator comprising in combination within a casing; a spring motor mounted within said casing; a rotatable shaft driven by said spring motor; a gear on said shaft; an electric generator mounted in said casing; a driving shaft therefor having a gear meshing with said first gear; an overrunning clutch between said driving shaft and generator to permit of winding up said spring motor in one direction without rotating said generator; a winding stem engageable at will to operatively rotate said driving shaft to wind said spring motor and spring urged into such winding position; a ratchet on said winding stem to hold said spring motor in such wound position; a bore in said casing for slidably supporting said winding stem; an operating knob external of said casing and operatively connected with said wind-

ing stem to slide this inwardly of the casing in its bore against said spring urging to a position to release said clutch and said ratchet and cause said spring motor to rotate said generator, to generate an impulse thereby; a cutout switch in the output circuit of said generator; and a cam mounted to move with said spring motor operating said switch to cut-out said generator when said spring motor is either fully wound or not wound at all and cut-in said generator when said clutch and ratchet are released, to cause said spring motor to drive said generator.

4. An emergency unit as claimed in claim 3 provided with an indicating device having indicia thereon mounted on said rotatable shaft driven by the spring motor to occupy a preselected posi-

tion when said spring motor is fully wound; and a window in said casing for observation of the indicia on said indicating device.
